UNITED STATES PATENT OFFICE.

WALTER G. DOTY, OF DAYTON, OHIO, ASSIGNOR TO THE ENTERPRISE MANUFACTURING COMPANY OF PENNSYLVANIA, OF PHILADELPHIA, PENNSYLVANIA, A CORPORATION OF PENNSYLVANIA.

CHOPPING-MACHINE.

1,145,755.

Specification of Letters Patent.

Patented July 6, 1915.

Application filed August 9, 1911. Serial No. 843,123.

To all whom it may concern:

Be it known that I, WALTER G. DOTY, a citizen of the United States, residing at Dayton, in the county of Montgomery and State of Ohio, have invented certain new and useful Improvements in Chopping-Machines, of which the following is a specification.

My invention relates to chopping or cutting machines adapted to reduce the material operated upon to minute portions by a severing or shearing action, and more particularly to the severing mechanism thereof.

The invention relates especially to food choppers for operating upon meat, vegetables, etc., but is not limited to such use but may be employed in machines for operating upon other materials.

It has been found in practice that the perforated die plate forming one of the opposing cutting members quickly becomes worn and dulled, thereby reducing the efficiency of the machine and resulting in a crushing or tearing action upon the material instead of the desired cutting or shearing action.

To provide a simple, economical and durable cutting plate which may be quickly and cheaply renewed when dull or worn, is one of the objects of the present invention.

A further object is to provide a face plate or cutting plate for the perforated die which will afford an improved cutting edge and provide clearance for the material as it passes through the perforations of the die plate or closure hereafter described.

A further object is to provide interchangeable face plates having openings of different dimensions for use with a single die or closure plate, thereby providing convenient and economical means for reducing the material to different degrees of fineness.

With the above primary and other incidental objects in view as will more fully appear in the specification, the invention consists of the features of construction, the parts and combinations thereof and the mode of operation or their equivalent, as hereinafter described and set forth in the claims.

Referring to the drawings, Figure 1 is a side elevation, partly broken away of an assembled chopper of well known form embodying the present invention. Fig. 2 is a detail view of the cutter member as ordi-

narily employed. Fig. 3 is a detail view of the perforated die plate or closure. Fig. 4 is a detail view of the perforated cutting or face plate. Fig. 5 is a detail sectional view of the closure plate with the face plate 60 in adjusted position thereon.

Like parts are indicated by similar characters of reference throughout the several views.

In the drawings the invention is shown as applied to a food chopper of well known construction. The machine comprises a receiver for the material comprising a barrel portion 1 and a hopper 2. Within the barrel 1 is located a revoluble spiral conveyer 3, operated by a handle 4, whereby the material is forced longitudinally through the barrel to the severing devices. At the discharge end of the receiver there is located a perforated closure plate 5 through the 75 perforations of which the material is forced by the helical conveyer 3. The closure plate 5 is provided with a central bearing sleeve 6 forming a bearing for the trunnion 7 of the helical conveyer 3. Carried upon a 80 shouldered extremity of the helical conveyer is a cutter member comprising the head 8 from which project radial cutting arms 9. The perforated die or closure plate is usually held stationary within the barrel by 85 means of a lug or key within the barrel engaging in a key way 10 in the plate. The plate is further secured in place by an adjustment ring or collar 11, screw threaded upon the extremity of the barrel. As usually constructed the cutter member rotates with the conveyer, the cutter being directly in contact with the perforated die or closure plate. It is obvious however that the operation of the parts might be reversed and 90 the plate rotated while the cutter member is held stationary.

The die or closure plates must be made of considerable thickness to successfully withstand the thrust or pressure to which it 100 is subjected by the helical conveyer. The great thickness of the plate in proportion to the diameter of the perforations therein necessitates the drilling of the holes in the plate, which is a tedious, laborious and expensive operation. When the cutter is used directly in contact with the die or closure plate, as is at present the usual practice, the edges of the perforations in the plate become worn or dulled, seriously interfering 105 110

with the successful operation of the machine. The usual practice is to replace the dull or worn plate with a new one, discarding the old plate. To materially reduce the cost of renewing the die or closure plates is one of the primary objects of the present invention.

In addition to the die or closure plate 5 and the cutter member, there is provided an 10 interchangeable face plate 12 which is interposed between the closure plate and cutter, and which may be secured by any suitable means in its adjusted relation with the closure plate. In the drawings, the closure plate 15 has been shown as provided with a marginal flange 13, having therein recesses 14. The face plate 12 carries marginal projections 15 which engage in the recesses 14 of the flange 13 to maintain the face plate in its relation 20 with the closure plate.

By connecting the thin face plate 12 to the closure plate 5 in the manner above described, the thin face plate 12 will accommodate itself more readily to the rotating knife 25 than the rigid plate heretofore used and, consequently, the knife and plate do not have to be ground to an accurate fit, which was necessary when both the plate and the knife were formed of rigid material.

The face plate 12 is constructed of comparatively thin material and may be readily formed from sheet metal by a punching or stamping operation at an extremely low cost. Being of thin metal the face plates 30 can be more thoroughly and evenly hardened or tempered than the closure or die plates as now used. Thus the face plate 12 which performs the cutting operation in conjunction with the cutter, and therefore 35 receives all the wear incident to the operation of the machine, may be replaced at but a small fraction of the cost of the perforated die or closure plate.

Furthermore the perforations of the face plate 12 are preferably slightly smaller than those of the closure plate, thus causing the margins of the face plate perforations to overhang the edges of the closure plate perforations, providing clearance within the 40 perforation of the closure plate, which facilitates the passage of the material therethrough, and furthermore the overhanging margin forms a cutting edge of greater efficiency than the flush face of the die or closure plate as heretofore used, and such overhanging edge will continue to perform its service until the face plate is worn away 45 beyond the margin of the closure plate, thereby giving an increased term of service. When the advance side of the face plate perforations have been worn dull, the face plate may be reversed upon the closure plate, thus presenting the opposite side of

the face plate perforations as the cutting edge, thereby affording a double term of usefulness. It is obvious that the face plate will operate successfully if the holes therein are equal in size to those of the closure plate and in registry therewith, as is shown in Fig. 1.

To vary the degree of fineness to which the material is reduced by the machine as commonly used, it is necessary to provide a plurality of closure plates 5 having perforations therein of greater or less size, where- 50 as by the use of the face plates herein described, a number of such face plates having perforations of different sizes may be employed with a single closure plate having perforations corresponding to the coarsest 55 grade desired. Such a collection of different face plates would be far less expensive than a similar collection of different closure plates as is now necessary.

From the above description it will be apparent that there is thus provided an improved mechanism for machines of the character described, possessing the particular features of advantage before enumerated as desirable, but which obviously is susceptible 60 of modification in its form, proportion, detail construction and arrangement of parts without departing from the principle involved or sacrificing any of its advantages.

Having thus described my invention I 65 claim:

1. The combination in a chopping machine, of a casing; a rotatable knife therein; a perforated, hardened thin sheet-metal cutting plate; a perforated rigid plate located 100 back of and supporting the thin sheet-metal plate; means for holding the thin sheet-metal plate from rotary movement relatively to the thicker rigid plate and permitting the free movement of said thin plate 105 parallel with the axis of the thicker plate and toward and from the face of the rotatable knife; and means for forcing the material against the thin sheet-metal plate.

2. In a chopping machine, a receiver for 110 the material, a perforated closure therefor, a cutter located adjacent thereto, a marginal recessed flange on the perforated closure, a detachable perforated face plate located within the marginal flange of the closure, 115 and peripheral projections on the face plate engaging the recesses of the marginal flange to maintain the face plate in fixed relation with the perforated closure.

In testimony whereof, I have hereunto set 120 my hand this 2nd day of August 1911.

WALTER G. DOTY.
